(57) **CLAIM**

The ornamental design for a multi-functional robot, as shown and described.

DESCRIPTION

FIG. 1 is a left perspective open configuration view of a multi-functional robot, showing the new design;

FIG. 2 is a left perspective closed configuration view of the multifunctional robot of FIG. 1;

FIG. 3 is a left perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.
